CLAIM

The ornamental design for a surgical staple cartridge, as shown and described.

DESCRIPTION

FIG. 1 is a front end view of the surgical staple cartridge.

FIG. 2 is a rear end view thereof.

FIG. 3 is a left side view thereof.

FIG. 4 is a right side view thereof.

FIG. 5 is a top plan view thereof.

FIG. 6 is a bottom plan view thereof; and,

FIG. 7 is a perspective view thereof.

The broken lines shown in the figures represent portions of the surgical staple cartridge that form no part of the claimed design.
